B. F. SMITH.

Manufacture of White Lead.

No. 22,679.

Patented Jan'y 18, 1859.

UNITED STATES PATENT OFFICE.

BENJAMIN F. SMITH, OF NEW YORK, N. Y.

IMPROVEMENT IN THE MANUFACTURE OF WHITE LEAD.

Specification forming part of Letters Patent No. 22,679, dated January 18, 1859.

To all whom it may concern:

Be it known that I, BENJAMIN F. SMITH, of New York, in the county and State of New York, have invented new and useful Improvements in the Manufacture of White Lead; and I hereby declare the following to be a full, clear, and exact description thereof, reference being had to the accompanying drawing, which forms part of this specification, and which represents a vertical section of an arrangement of apparatus for carrying into effect my invention.

My invention relates to the manufacture of white lead according to the "dry process," in which metallic lead under the influence of heat and moisture is oxidized and combined with carbonic acid when exposed to the action of acetic vapors or vapors from vinegar; and my invention consists in a peculiar disposition of the lead in the converting-chamber, insuring its effectual exposure to the corroding action of the said vapors; and it further consists in the manner of extracting from said chamber the carbonate formed therein previously to subjecting it to the washing and drying process, whereby the workmen engaged in such manufacture are protected against the injurious effects attendant thereon when conducted according to previous modes.

To distinguish my invention from preceding methods, I would state that the ordinary process as practiced in Holland, France, and England consists in first placing rolled lead sheets spirally arranged in low pots containing vinegar and wine lees. These pots are put into chambers dug in the ground and surrounded with horse-dung, by which arrangement a temperature of about 50° centigrade is produced, the same being necessary to effect the corrosion of the metal in about six weeks. The horse-dung answers a double purpose—namely, that of producing heat and that of furnishing by its decomposition carbonic acid. After this exposure the lead sheets are taken out of the pots and unrolled, when the carbonate formed from the lead crumbles in pieces, and is collected to be broken between wooden rollers and afterward ground and mixed with water, and the pasty substance thus produced placed in molds, where it remains three or four days, is dried, and sold in cakes. Besides the enormous expenditure of time, labor,

and apparatus incidental to such method of manufacture, said process is most prejudicial to the health of the workmen engaged in carrying it out, particularly that portion of it which relates to the detaching of the carbonate of lead from the metallic sheets. These sheets are required to be shaken and tapped to detach adhering dust and powder that form a considerable and valuable portion of the product. Such powder, being very light, forms a floating cloud, which the workmen necessarily breathing they inhale a deadly poison. I am also aware that by the Austrian method of manufacture the lead sheets are hung over cross-bars in chambers, in the bottom of which vinegar and wine lees are allowed to evaporate to effect the corrosion of the sheets. These chambers are heated by horse-dung, that supplies also the necessary carbonic acid, or by steam-pipes or hot-air flues surrounding said chambers. The sheets thus corroded are considerably increased in thickness and contain a large quantity of acetate of lead, which has to be detached and the carbonate carefully and repeatedly washed. Both of these briefly-described processes are expensive and dangerous to the health of the workmen. In the former process a great quantity of metallic lead remains as a residuum of the manufacture, and this requires to be remelted, while in the latter process the production of acetate of lead is so great that it may be detached in perfect crystals hanging about and around the sheets.

My improvement, as will appear from the following description, obviates the defects before mentioned as incidental to either of the processes just described.

Thus I first prepare in any convenient manner the lead in small spangles of (say) two inches in length, one-fourth of an inch width, and of the thickness of ordinary letter-paper (more or less) arched in their cross-section and of arched or irregular form longitudinally, such as would be formed by melted lead issuing from a fine orifice and falling on a rapidly-revolving corrugated cylinder, cooling and breaking the stream and throwing the lead off in detached pieces. These spangles I pile or throw upon racks placed successively under said revolving cylinder. The racks may be made of trellis-work and about

four hundred of them be used in each converting-chamber, which chamber may be about six feet high, twelve feet long, and six feet wide, and should be made with an inclined bottom, as shown in the accompanying drawing. The racks *a* I place in said chamber *A* in double rows by arranging them first in the rear and piling them up to or near the top, and gradually advancing to build up a row or rows of other racks in front of them. The chamber then containing the racks with spangles on them is carefully closed and luted. Tubes or pipes *x y* are provided in the chamber at its bottom, establishing a communication between said chamber and a boiler or vinegar tub *B*, the tubes being closed when required by trap-valves *x y*. At or near the top of the chamber is an opening *b*, closed by a trap-valve *g*, which is occasionally lifted to allow foul air to escape—that is, air which was in the tube and chamber previous to commencing work, and which, being lighter than carbonic acid, will rise and be expelled, said opening also serving to increase the circulation when the chamber is too densely filled and choking of the passages or obstruction is produced by means of a force-pump or section-blower applied thereto to effect a forced circulation.

I would state here that it may be advantageous to combine the manufacture of white lead with that of vinegar. The vapors rising from the fermenting-tub in the latter manufacture may thus be made available and collected and forced into the converting-chamber *A*, and by arranging the said chamber above or on a level higher than the outlet to the vapor from the fermenting-tub the natural ascent of the vapors will cause them to enter the chamber. Such combination of manufacture, however, I do not claim, as it is in common use abroad, and has been described in printed publications of date long prior to this proposition of such economy. The chamber *A*, I also provide with pipes *c c*, entering at the top and serving to conduct the carbonic-acid gas into the chamber simultaneously with the corrosion of the lead by the acetic vapors. It will be apparent that by this arrangement the most perfect circulation is produced, the carbonic-acid gas descending, while the acetic vapors ascend among and through the several racks on which the spangles rest, and which, filling the chamber or thereabout, admit of no through-current in one direction more than another, but cause the gas and vapor to "worm" their way in and among the spangles, and, as due to their arched or irregular form and thinness, to act with perfect equality, certainty, and effect in converting the lead as required. The distribution of the lead spangles on the racks may be from one to two inches in depth each successive series of racks or frames, which allows of the fumes from below readily, but not too readily, passing through the mass to the top of the chamber, where the foul air may escape. In all

other methods the lead is arranged with so much vacant space intervening that the fumes are at liberty to circulate where they find the largest drafts, and the consequent result is very unequal corrosion of the metallic lead. The lead in spangles thus acted on in a perfect, regular, and equal manner, or thereabout, by the acetic fumes is soon converted into a sub-acetate of lead, which in turn is decomposed by the action of the carbonic-acid gas freeing the acetic acid that is again made available for further action on the metallic lead, and which process is being continually repeated. In from five to ten days the lead spangles become by this treatment thoroughly corroded, leaving in the chamber, instead of metallic lead, pure carbonate of lead intermixed, but only slightly, with acetate of lead, which is converted by an after process into carbonate of lead; or the product from the chamber may be freed from the acetate of lead by repeated washing.

The chamber being filled with the converted product—that is, carbonate of lead—I proceed to extract it from said chamber as follows: A pipe *d* (shown in the accompanying drawing) is made to convey from a boiler or tank steam or water into the chamber. When steam is used, I introduce a jet of it, the object of which is to saturate the carbonate of lead and so moisten it that the whole mass shall acquire a pasty consistency somewhat like mortar, and the said jet further serves to expel the foul gases and air contained in the chamber, and which, being specifically heavier, will be displaced and fall in the lower part of the chamber, from which they may escape by lifting a trap-valve. In this way the workmen are safely guarded against the obnoxious dust and vapors which according to previous methods they have been forced to inhale while removing the lead from the chamber to the washing-tub.

When the pipe *d* last referred to is used to convey water, I make or attach it as a hose, in order that it may be moved or worked from the outside of the chamber in such a manner as to project its jet or stream in every direction within the chamber. In this case the washing-tub is placed immediately under the outlet of the chamber, and the carbonate of lead is washed out of the chamber without much delay or difficulty and entirely by reason of the inclination given the bottom of the chamber, whereby all handling for transfer of obnoxious matter to the washing-tub is avoided.

What I claim as my invention, and desire to secure by Letters Patent, is—

1. The manner of filling the chamber with metallic lead by means of the open-work tables or racks on which the lead in detached pieces rests, arranged one above the other in successive and close series, substantially as described, and whereby a more thorough and equal circulation of the fumes or gases among the lead is produced.

2. Constructing the converting-chamber with an inclined bottom, substantially as and for the purposes set forth.

3. The method herein described of extracting from the converting-chamber the carbonate of lead and other incidental products by means of a current or currents of water passing through said chamber from top to bottom, substantially in the manner and for the objects herein set forth.

4. Subjecting the carbonate of lead and

other incidental products previous to their extraction from the converting-chamber to the action of steam, substantially in the manner and for the purposes specified.

In testimony whereof I have signed my name to this specification before two subscribing witnesses.
